UNITED STATES PATENT OFFICE.

MAX KLEIN, OF NEW YORK, N. Y., ASSIGNOR TO MOSSE, INCORPORATED, OF NEW YORK, N. Y.

DESIGN FOR A DOILY.

Application filed May 22, 1925. Serial No. 13,536. Term of patent 7 years.

To all whom it may concern:

Be it known that I, MAX KLEIN, a citizen of the United States, residing at New York city, county and State of New York, have invented a new, original, and ornamental Design for a Doily, of which the following is a specification, reference being had to the accompanying drawing, forming a part thereof.

The figure is a plan view of a doily showing my new design.

The mesh of the scalloped lace as indicated on the bottom of the doily is repeated throughout its extent.

I claim:

The ornamental design for a doily, as shown.

In testimony whereof, I affix my signature.

MAX KLEIN.
